UNITED STATES PATENT OFFICE.

WALTER HOAGG, OF DETROIT, MICHIGAN.

BEET-TOPPER.

1,401,079.

Specification of Letters Patent. Patented Dec. 20, 1921.

Application filed December 15, 1919. Serial No. 344,868.

To all whom it may concern:

Be it known that I, WALTER HOAGG, a citizen of the United States, residing at Detroit, in the county of Wayne and State 5 of Michigan, have invented new and useful Improvements in Beet-Toppers, of which the following is a specification.

This invention relates to beet topers and embodies among other features means for 10 engaging and twisting the beet tops by a plurality of cutting blades to effectively and quickly sever the tops from the beets.

Other objects and advantages will appear when the nature of the invention is better 15 understood from the following detail description when taken in connection with the accompanying drawings, the invention residing in the construction, combination and arrangement of parts as claimed.

20 In the drawings forming part of this specification like numerals of reference indicate similar parts in the several views and therein:

Figure 1 is a side elevation of the machine.
25 Fig. 2 is a top plan view.

Fig. 3 is a view similar to Fig. 1, looking from the opposite side of the machine.

Fig. 4 is a vertical sectional view taken 30 on line 4—4 of Fig. 1, looking in the direction of the arrows.

Fig. 5 is a sectional view taken on line 5—5 of Fig. 2.

Fig. 6 is a sectional view taken on line 6—6 of Fig. 2.

35 Fig. 7 is a transverse sectional view taken on line 7—7 of Fig. 2.

Fig. 8 is an enlarged detail view of one of the puller arms.

Fig. 9 is a sectional view taken on line 40 9—9 of Fig. 1.

Fig. 10 is an enlarged detail view of the adjustable connection for the frame of the machine.

The machine forming the subject matter 45 of my invention comprises a frame including spaced side members 10 and end members 11 and 12 respectively. One of the side members 10 is offset as at 13 adjacent the rear end of the machine to accommodate the root 50 pulling mechanism to be hereinafter described. The machine is strengthened by a transverse member 14 which connects the sides of the frame as shown. The frame of course is mounted upon wheels, preferably 55 three in number. The front wheel 15 is of the caster type, while the wheels 16 and 17

respectively are the tractor wheels. One or both of the tractor wheels may be provided with calks 18 for obtaining an effective purchase upon the ground.

60 The mechanism for extracting roots and beets from the ground, consists of a pair of spaced disks or wheels 20 keyed upon a shaft 21 journaled between the side members 10 of the frame. The shaft 21 at a point beyond one side of the machine is provided with clutch members 22 and 23 respectively. A lever 24 is utilized for throwing the clutch members into and out of engagement. A drive chain 25 is trained over a gear 26 65 forming part of the clutch member 23, and over a gear 27 fixed upon the hub of the tractor wheel 17. When the clutch members are in operative association, it is manifest that the shaft 21 is rotated from the 70 tractor wheel 17. The shaft 21 is driven a few revolutions faster per minute than the drive wheel 17. Each of the disks or wheels 20 is provided with a plurality of openings 75 28 adjacent the periphery of the wheel. Arranged to slide through each opening is a root or beet puller arm 30. The arms are 80 arranged horizontally, while the arms of the respective disks or wheels 20 are aligned to work in pairs, the arms of each pair being 85 moved toward and away from each other in successive order and at predetermined intervals. Arranged between each wheel or disk 20 and the adjacent side of the frame is a cam 31 secured to the frame by means of the 90 braces or supports 32. The arms 30 are held in place by guide disks 33, while the outer end of each arm has journaled thereon a pair of spaced wheels 34 which engage the 95 opposite faces or sides of the adjacent cam 31. The inner ends of the arms 30 are relatively broad and have secured thereto tips 35 of rubber or other soft material. The parts are so arranged, that when the machine is in operation and the wheels 20 rotated, the arms 30 of the respective wheels are moved toward each other in pairs as the wheels approach the ground to effectively engage the roots or beets to be extracted. The arms are moved in this manner by reason of their association with the 100 cams 31, while the rubber tips 35 allow the arms to obtain an effective purchase upon whatever is being extracted from the ground. As the wheels 20 continue to 110 rotate, the beets or roots are extracted from the ground and carried between the arms

to a point adjacent the top of the wheels. At this point the rollers 34 start to travel over the offset portion 36 of each cam 31, and consequently move the arms of each 5 pair away from each other, releasing the beet or root and depositing the same upon an endless conveyer 37. The conveyer 37 carries the beets in the direction of the forward end of the machine upon which the topping 10 mechanism is mounted.

While the machine is primarily intended as a beet puller and topper, it is susceptible for use in pulling beans, onions and other kinds of roots, and its general application 15 is contemplated by the claims. The endless conveyer 37 comprises the chains 38 which are trained over the cog wheels 39 and 40. The links of the chain are provided with lugs 41 and to the lugs of the respective 20 chains are connected the rods 42. The conveyer with the rods 42 is used for sugar beets or heavy roots, but when the machine is used for pulling and discharging beans or small roots, a canvas belt or the like will 25 be strapped over the chains and rods 42 as will be understood. The conveyer is driven from the shaft 21.

Disposed in advance of the conveyer 37 is the endless conveyer forming part of the 30 topping mechanism. This conveyer is of a construction somewhat similar to the conveyer 37, except that it extends across the entire width of the machine. The conveyer embodies spaced parallel shafts 44 upon each 35 of which is fixed a plurality of sprocket wheels 45, preferably three in number. Chains 46 are trained over each pair of sprockets, while the links of each chain are provided with lugs 47 which are connected 40 with the parallel rods 48 which connect the respective chains. The shafts 44 are journaled in suitable bearings 49 secured to the sides of the machine. Each of the rods 48 carries a plurality of plates 50 which are 45 set at an angle with respect to the rods so as to give the conveyer a screw pitch. The beets are deposited upon the conveyer 37 and travel thereon with their tops toward the front of the machine, the conveyer 37 trans- 50 ferring the beets onto the conveyer forming part of the topping mechanism. A sprocket wheel 51 is fixed upon the shaft 44 and trained over this sprocket wheel, and the sprocket wheel 52 fixed upon the shaft 53 55 is an endless chain 54 which operates the conveyer. The tops are then rolled between two screw shafts 56 which are arranged in superimposed relation in advance of the conveyer and journaled between the spaced up- 60 rights 57. The screw shafts are provided with gears 58' at one end which mesh with each other, while one of said shafts is provided with a sprocket wheel 58. Trained over the sprocket 58 and the sprocket 59 65 fixed upon the shaft 44, is a chain 60 for

operating the spiral or screw shafts 56. These shafts are driven at the same speed or ratio per foot as the topper conveyer. As the tops pass between these two shafts 56, they are screwed against and between two 70 blades 61 and 62 respectively, and consequently the tops are cut off. The blades are carried by angular shaped bars 63 and each bar has one end connected with a bracket 64 by means of a slot and pin 65 and 66 re- 75 spectively. The blades can consequently be adjusted toward and away from each other by means of this construction. Corresponding extremities of both the blades and their supporting bars are spread to provide a 80 flared entrance opening or passage for the tops of the beets. After the tops have been cut from the beets, the beets are conveyed into a suitable trough, while the tops are conveyed into a suitable trough, the troughs 85 being disposed relatively to discharge the beets and tops from the side of the machine in spaced rows. As shown in Fig. 3 the blades 61 and 62 are arranged between the spiral shafts 56 and the conveyer of the top- 90 ping mechanism.

The machine may be adjusted vertically to properly position the extracting mechanism with relation to the ground according to the height of the crop being pulled. For 95 this purpose a plate or the like 70 is fixed to the axles, and carries threaded sleeves 71. The plate 70 is relatively adjustable with respect to guides 72 longitudinally slotted as at 73 and in which slots the sleeves 71 100 travel. A lift screw 74 is passed through each sleeve, while each screw is provided with a hand wheel 75 for turning the same. One of the hand wheels is connected directly with the adjacent screw, while the 105 screw at the forward end of the machine is provided with a bevel gear 76 which meshes with a bevel gear 77 carried by a horizontally disposed rod 78 journaled in a bearing 79. The hand wheel 75 for this screw is 110 fixed upon the rod 78 adjacent the driver's seat as shown.

The machine is designed to meet all the requirements of a beet extracting and topping mechanism. If necessary, the ordinary 115 beet plow may be used in advance of the machine to loosen extremely hard ground or land. As hereinbefore stated, the machine may be used for pulling and discharging all kinds of roots, such as onions, beans, etc. When the machine is used for extracting roots of this character, the topping mechanism can be removed, and an endless carrier mounted upon the machine at right angles to the conveyer 37. Arranged in advance 120 of the extracting mechanism are guards 80 to direct all the tops, leaves or vines between the adjacent extremities of the arms 30, so that the latter will engage the same.

While I have shown and described what 130

I consider the preferred embodiment of the invention, I desire to have it understood that I do not limit myself to the exact arrangement illustrated, and that such changes may be resorted to when desired as fall within the scope of what is claimed.

5 What is claimed is:

1. In a beet topping machine, topping mechanism comprising spaced upper and lower cutting blades, having their cutting edges arranged to provide a flared entrance for the beet tops, means for conveying the beets toward the blades and moving the beet tops between the cutting edges thereof, said 10 means being disposed in advance of the blades, and a pair of spiral shafts arranged at the opposite sides of the blades, said shafts being slightly spaced and arranged to engage the tops and screw the latter against the cutting edges of the blades for the purpose specified.

2. In a beet topping machine, topping mechanism including spaced upper and lower blades, an endless conveyer disposed 15 in advance of the blades and arranged to convey the beets toward the latter for moving the beet tops between the cutting edges of said blades, a pair of spiral shafts arranged

in spaced superimposed relation and at the opposite sides of the blades, said shaft being arranged to receive the tops of the beets after passing between the cutting edges and screwing said tops against said blades for the purpose specified, and means for rotating 30 said spiral shafts.

3. In a beet topping machine, topping mechanism comprising spaced upper and lower cutting blades, an endless conveyer arranged in advance of said cutting blades, and adapted to convey the beets toward said blades and position the tops of the beets between the cutting edges thereof, a pair of superimposed spiral shafts arranged at the other side of said blades, gears carried by 40 the respective shafts and meshing with each other, means for operating said endless conveyer, and means for driving said shafts from said endless conveyer, said shafts being arranged and designed to receive the beet tops and screw the latter against the cutting edges of said blades for the purpose specified.

45 In testimony whereof I affix my signature.

WALTER HOAGG.
